(57) **CLAIM**

The ornamental design for a headband for headlamp as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevational view of a headband for headlamp, showing the new design; and,

FIG. 2 is a front elevational view thereof in use.

The broken lines depict environment and form no part of the claimed design.
